INVENTOR

Frederick M. Robert Burns

UNITED STATES PATENT OFFICE

107,853

DESIGN FOR A TEXTILE FABRIC

Frederick M. Robert Burns, New York, N. Y.

Application December 9, 1937, Serial No. 73,509

Term of patent 3½ years

To all whom it may concern:

Be it known that I, Frederick M. Robert Burns, a citizen of the United States of America, residing in New York city, in the Borough of Manhattan, county and State of New York, have invented a new, original, and ornamental Design for a Textile Fabric, of which the following is a specification, reference being had to the accompanying drawing, forming part thereof, wherein,

The figure is a plan view of a textile fabric showing my new design.

I claim:

The ornamental design for a textile fabric, substantially as shown.
